UNITED STATES PATENT OFFICE.

HERMANN LEMP, OF LYNN, MASSACHUSETTS, ASSIGNOR TO ELIHU THOMSON, OF SWAMPSCOTT, MASSACHUSETTS.

MOTION-CHECKING DEVICE.

SPECIFICATION forming part of Letters Patent No. 692,876, dated February 11, 1902.

Application filed November 17, 1900. Serial No. 36,868. (No model.)

To all whom it may concern:

Be it known that I, HERMANN LEMP, a citizen of the United States, residing at Lynn, county of Essex, State of Massachusetts, have 5 invented certain new and useful Improvements in Motion-Checking Devices, (Case No. 1,936,) of which the following is a specification.

In my prior applications, Serial No. 686,063, filed July 15, 1898, and Serial No. 23,990, filed 10 July 18, 1900, renewed November 1, 1901, Serial No. 80,823, I have described and claimed devices for checking motion between two moving mechanisms or parts. The devices illustrated consist in general of a casing and a piston, which are movable with respect to each 15 ton, which are movable with respect to each other and which are controlled by a valve actuated by an operating-handle. As the handle is moved from a given position it first opens the valve and then moves one member with 20 respect to the other. In arrangements of this kind there is of necessity a small amount of lost motion.

The present invention contemplates motion-checking devices of the same general character; but instead of utilizing the first part of 25 the movement of the operating-lever to open the valve the parts are so arranged that it is necessary to give the handle a different movement to open the valve than is required to 30 move a part or parts with respect to another part or parts. With such a device there is no lost motion between the operating-handle and the member or element to be moved. Another advantage in this construction re- 35 sides in the fact that the locking mechanism can be readily rendered inoperative if for any reason it is so desired.

Referring to the accompanying drawings, which illustrate an embodiment of my invention, Figure 1 is a vertical section of a motion-checking device. Fig. 2 is a detail view of the operating-handle therefor, showing certain of the parts in section. Fig. 3 is a detail view in elevation of part of the handle. Fig. 45 4 is a plan view of the handle. Figs. 5 and 6 are respectively a plan and side elevation of the piston. Fig. 7 is a vertical section through the piston and controlling-valve. Fig. 8 is a sectional view of the piston, showing the controlling-valve in a closed position. Fig. 9 is a

horizontal sectional view taken on the line 9 9 of Fig. 1 looking in the direction of the arrow. Fig. 10 is a sectional view of a slight modification. Fig. 11 is a horizontal sectional view of the piston and valve of the type illustrated in Fig. 10 and shown in the operative position. Fig. 12 is a section of a slight modification of the steering-handle. Fig. 13 is a plan of the same, and Fig. 14 shows the motion-checking device applied to the steering 60 mechanism of a vehicle.

Referring to Fig. 1, A represents a body or casing, and mounted for movement therein is a piston B. Situated above the piston is a chambered cover C, which closes the casing 65 above the piston. Extending downwardly from the cover is an extension C', which is curved on its inner wall concentric with the center of the piston, and the outer wall is shaped to conform to the casing A. The piston 70 is mounted eccentrically with respect to the casing and, as shown, two chambers D D' are provided. These are filled with a normally quiescent body of fluid—such as glycerin, for example. I have found that to be a very satisfactory fluid, since it does not freeze in winter; but oil or other fluid may be employed if desired. The casing is supported by lugs E, formed on the front thereof. When the checking device is applied to a vehicle, as illustrated in Fig. 14, the lugs are clamped around the fixed axle F, and when applied to other apparatus the casing is connected to one part 80 and the piston to another, the parts being so arranged that they are capable of movement 85 with respect to each other.

The piston B consists of a hub having shoulders formed therein and a solid wing or blade B', which extends at right angles thereto. The hub of the piston is chambered out to receive the valve G, and the opening at the bottom of this chamber is closed by a screw-threaded plug H. The chamber in which the valve is located communicates with a passage formed in the casting C through an opening 95 I. This passage I forms a relief, so that the valve may readily be raised. In addition to this other means are provided, which will be hereinafter described. On opposite sides of the piston are ports J. When the valve is 100

in the operative position, fluid can flow from the chamber D on one side of the piston to chamber D' on the other.

The valve G for controlling the operation of the device consists of a piston-like piece having a groove G' formed in its periphery and a central passage G². The stock forming the upper end of the passage is screw-threaded to receive the end of the valve-operating rod K. The lower end of the operating valve-rod K is somewhat enlarged and is provided with a central opening which communicates with the vertically-extending passage G² in the valve. In addition to this are holes L, which communicate with the chamber containing the piston. This arrangement acts as a relief for the fluid above the valve when it is actuated. Owing to the construction of the parts, the chamber above the valve is always filled with the same fluid as is contained in the chamber of the casting C and in the chambers D and D'. As the valve is raised it acts like a piston, and the fluid is forced from the valve-chamber through the passage I and also through the holes L into the passage G², and thence to that portion of the chamber below the valve. When the valve is in the position shown in Figs. 7 and 8, the parts are locked against movement; but when the valve is raised, as is shown in Figs. 1 and 9, fluid is permitted to flow from the chamber D into the chamber D'. The operating-handle M is pivotally connected to a clamp M', that is secured to the upper end of the steering-tube N. The lower end of the tube N is connected to the piston-hub by means of a flexible connection N'. The object of this flexible connection is to permit the swinging steering-handle and the steering-tube to move with the body of the vehicle independent of the casing and piston, which are secured to the running-gear or framework. The valve-rod K is inclosed by the tube N and is also provided with a flexible connection K' for the same reason. As illustrated, this flexible connection, as well as connection N', consists of a universal joint; but any suitable form of flexible connection may be employed in either or both instances, and I aim to embrace such constructions in the claims. The upper end of the valve-rod is provided with rack-teeth, with which the teeth of the pinion O mesh, which pinion is rigidly mounted on a shaft that is actuated by the swinging operating-handle M. In order to close the piston-controlling valve G whenever the pressure of the hand is removed from the operating-lever, a coil-spring P is provided, which tends at all times to lift the handle, and consequently rotate the pinion O in a manner to close the valve. In operating the check the handle M is first depressed, which raises the valve to the position shown in Fig. 1, after which the piston and the parts attached thereto may be moved. As soon as the pressure is removed from the handle the spring P will raise the handle and close the valve. After

the handle has been depressed to raise the valve it is employed to move the members A and B with respect to each other, and while this is taking place the valve is inoperative—that is to say, it was set by the original movement of the handle. On the other hand, the valve may be actuated without changing the angular position of the members or steering-wheel by simply moving the handle up and down or by twisting it, as illustrated in Figs. 10 to 13.

When for any reason it is considered desirable to operate the mechanism without using the checking device, it may be done by maintaining the handle in the depressed position. This might be desirable in a crowded street, where the steering movements were comparatively sudden and abrupt. On the other hand, when the vehicle is traveling in a section of country where the path of travel is comparatively unobstructed the pressure may be removed from the handle and the check will hold the parts in their operative position, and this without making any change in the structure or arrangement of parts.

Referring to Figs. 10 and 11, I have shown a slight modification of my invention, in which the valve G is rotated from operative to an inoperative position instead of being moved vertically, as is the case in the previous figures. The upper end of the valve-rod K is provided with a bevel-gear, which meshes with a similar gear carried by the operating-handle M. The steering is accomplished through the steering-tube N (illustrated in dotted lines) and the handle M. The valve G is tapered, so as to make a working fit with the tapered valve-seat formed in the piston. The valve is normally retained in the raised position by means of the coiled extension-spring Q. The lower end of the chamber containing the valve is closed by a screw-threaded plug H. As illustrated in Fig. 11, the valve is in a position to permit fluid to flow from the chamber D into the chamber D'. Twisting the handle more or less will vary the valve-opening, and consequently the rate of transfer of the fluid in the main chambers. In certain aspects a construction of this kind presents advantages over the one previously described in that it is unnecessary to provide relief-passages, since there is no piston-like action of the valve. In operating the device the handle M is twisted in either direction from a given position, which in turn transmits motion to the valve-rod K through the bevel-gear. As the valve is turned the passage G' comes into line with the openings or ports J in the passage or moves out of line with the ports, depending upon the direction in which the handle is twisted. When the valve has been set in the position shown in Fig. 11, the handle may be swung around the axis of the steering-tube N as a center, and as long as the valve is kept open the moving of the members with respect to each other may be freely accomplished. In order to lock

the parts, the handle is twisted in a direction which will close the passage between the chambers D and D'.

Referring to Fig. 14, I have illustrated my invention in connection with the steering-wheels of a vehicle. R represents the steering-wheels, which are mounted on short axles that are carried by the fixed axle or support F. Secured to the short axles are levers S, which in turn are connected to the lever T, that is secured to the moving part of the checking device. In the present instance the piston is the moving element; but it is to be understood that the piston could be made stationary and the cylinder arranged to move. The casing A is rigidly secured to the front axle, and as the handle M is operated the angular position of the wheels will be freely changed.

20. What I claim as new, and desire to secure by Letters Patent of the United States, is—

1. In a motion-checking device, the combination of members movable with respect to each other, a body of normally quiescent fluid

25 acting as a lock between the members, a positively-actuated valve for controlling the action of the fluid, a handle which is rigidly connected to one of the elements and imparts movement thereto, and a positive mechanical connection between the handle and the valve.

2. In a motion-checking device, the combination of members movable with respect to each other, a body of normally quiescent fluid

35 acting as a lock between the members, a positively-actuated valve for controlling the action of the fluid, a handle which is rigidly connected to one of the elements and is positively connected to the valve and so arranged that when it is moved in one direction it actuates

40 the valve and when moved in a different direction moves one of the members.

3. In a motion-checking device, the combination of members movable with respect to each other, a body of normally quiescent fluid

45 acting as a lock between the members, a positively-actuated valve for controlling the action of the fluid, a swinging handle rigidly connected to one of the members and capable of moving in a horizontal as well as a vertical 50 plane, and a mechanical connection between the valve and the handle which is operative during the movement of the handle in one plane but not in the other.

4. In a motion-checking device, the combination of members movable with respect to

55 each other, a body of normally quiescent fluid acting as a lock between the members, a positively-actuated valve for controlling the action of the fluid, a swinging handle rigidly connected to one of the members and capable of moving in a horizontal as well as a vertical 60 plane, and a jointed connection between the handle and the valve which is operative only when the handle is moved in the vertical plane.

5. In a motion-checking device, the combination of two members movable with respect

to each other, a body of normally quiescent fluid acting as a lock between the members, a valve mounted in one of the members, a handle for moving the member carrying the valve, and a mechanical connection between the valve and the handle.

6. In a motion-checking device, the combination of two members movable with respect to each other, a valve carried by one of the members, a tube connected to and actuating one of the members, an operating-handle secured to the tube, and a valve-operating means which passes through the tube for controlling the valve.

7. As an article of manufacture, a motion-checking device, comprising two main members capable of movement with respect to each other, a positively-actuated valve carried by the movable member, a tube secured to the moving member, a valve-operating rod which passes through the tube, and actuating means for the movable member and the valve-rod.

8. In a motion-checking device, the combination of two elements movable with respect to each other, a valve carried by one of the elements, a tube rigidly connected to the valve-carrying element, an operating-handle secured to the tube, and a valve-operating rod which passes through the tube.

9. In a steering-check for vehicles, the combination of a member secured to a fixed part of the vehicle, a member moving with a steering-wheel, a device for locking the members together, a tubular actuator, a flexible connection between the actuator and the moving member, a means for actuating the lock, and a flexible connection between said means and the lock.

10. In a steering-check for vehicles, the combination of a stationary member, a moving member, a device for locking the members together, a tube, a jointed connection between the tube and one of the members, a means for controlling the action of the lock, a rod passing through the tube, and a jointed connection between the rod and the lock-controlling means.

11. In a steering-check for vehicles, the combination of a steering-wheel, a pair of members which are movable with respect to each other, a double-acting lock between the members, a steering-tube connected to the movable member, a means extending through the tube for actuating the lock, a handle secured to the tube for moving the steering-wheel, and a connection between the handle and the lock-actuating means which is inoperative in so far as the valve is concerned when the steering-wheel is being moved, but is operative when the handle is moved in a manner other than that required to steer.

12. In a motion-checking device, the combination of a movable and a stationary member, a lock for securing the members against relative motion, comprising a body of normally quiescent fluid, and a valve for con-

trolling the lock, comprising a piston-like structure having a relief-passage through which a certain amount of the fluid is transferred when the valve is actuated, and other passages permitting the main body of fluid to circulate, and means for positively actuating the valve.

13. In a motion-checking device, the combination of a casing, a piston mounted therein, a valve-chamber formed in the piston, a piston-valve mounted therein, a relief-passage shunting and affording a relief for the piston-valve, and other passages for permitting fluid to pass from one side of the piston to the other, and a rod for positively actuating the valve.

14. In a motion-checking device, the combination of two members movable with re-

spect to each other, a body of normally quiescent fluid forming a lock between the members, a positively-actuated valve, a rod for actuating the valve, a handle for moving the members and actuating the valve, a flexible connection between the handle and the rod, and a means for moving the handle in a direction to actuate the valve-rod as soon as the hand of the operator is removed from the handle.

In witness whereof I have hereunto set my hand this 14th day of November, 1900.

HERMANN LEMP.
